SKI BINDING

Jerome E. Barieau, Auburn, Calif.

Application October 28, 1935, Serial No. 47,011

(Cl. 280—11.35)

This invention relates to equipment for skis and is directed in particular to ski bindings.

Although there are many types of ski bindings available on the market, there are none which are readily adapted for use on skis at winter resorts and the like for rental purposes and where the ski bindings must be capable of easy adjustment to the shoe size of the individual wearing the skis.

It is therefore my principal object to provide a ski binding capable of being quickly and easily adjusted to the shoe size of a person who is to use the skis to which my improved ski bindings are attached, and in particular to provide toe irons which may be adjusted laterally of the skis.

Additional objects of my invention are to provide an adjustable sole clip in connection with the toe irons of the bindings and to provide heel clips in connection with the heel strap.

A further object of my invention is to provide a novel form of buckle for use between the ends of the heel strap and the adjacent ends of the connecting straps, which extend forward to the toe irons on each side of the ski.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of my improved ski binding.

Figure 2 is a top plan view of my improved adjustable toe irons.

Figure 3 is a longitudinal section of line 3—3 of Figure 2.

Figure 4 is a fragmentary side view of the forward end of a toe iron.

Figure 5 is a top plan view of a modified form of adjustable toe irons.

Figure 6 is a longitudinal section of line 6—6 of Figure 5.

Figure 7 is a perspective view of the heel strap, heel clips, buckles and connecting straps of my improved ski bindings.

I refer now in particular to the characters of reference on drawings, and especially at present to the ski bindings shown in Figures 1—4, inclusive.

The numeral 1 denotes a ski upon which my

preferred form of toe iron unit is mounted. The toe irons 2 are supported above the upper surface of the ski by means of flat, transverse tongues 3, extending from the lower portion of the toe irons across the surface of the ski in side by side relationship. These flat tongues are secured in slideable relationship to each other by an anchor plate 4, having grooves therein through which the tongues 3 slidably project, as illustrated in Fig. 3 of the drawings. The anchor plate 4 is rigidly fastened to the upper surface of the ski by means of suitable screws 5.

The toe irons are disposed in forwardly converging relationship, each forward end being slotted as at 6. These slotted ends of the toe irons project into grooved nuts 7, threaded on each end of a transversely extending bolt 8. The threads on the separate ends of bolt 8 are right and left-hand threads, respectively, in order that the nuts 7 may move toward or away from each other with rotation of the bolt. The bolt 8 is rotated by means of a key which removably engages in a non-circular projection K on one end of the bolt. The bolt 8 projects through and is rotatably supported intermediate its ends by a housing 9, while a collar 10 rigid with the bolt, prevents movement of the bolt through the housing but does not restrict rotation of the bolt. The housing 9 is formed as an integral part of a base plate 11, which is secured to the ski by the forward screws 5 which secure the adjacent end of the anchor plate to the ski. This is accomplished by having a portion of the base plate overlap the adjacent portion of the anchor plate. The plate 11 is turned up along the front edge to form a flange 11A, which protects the exposed bolt from possible damage.

To adjust the toe irons, a key is engaged with the projection K and the bolt rotated, causing the nuts 7 to move toward or away from each other, which in turn moves the toe irons in a corresponding direction. The slideable tongues 3 guide the toe irons and keep the same in proper relative positions.

The toe irons are provided with sole clips 12, adjustably and removably secured thereto in the following manner. Each toe iron is provided with a series of vertically spaced holes 13 connected together by slots 14 of less width than the diameter of the holes. The sole clips 12 are rectangular and are provided on one side with a neck 15 having substantially the same length as the thickness of the toe irons, a thickness slightly less than the width of slots 14 and a width substantially the same as the diameter of the

holes 13. A wing 16 is formed on the outer end of the neck 15, said wing being capable of insertion through the slotted series of holes. The sole clips are mounted in any desired hole 13 by merely passing the wing 16 through the slotted series of holes, moving the neck up or down to the desired hole and then turning the sole clip to a horizontal position, which causes the neck 15 to bind in the hole, due to the fact that the width of the neck and the diameter of the hole are substantially the same size. Also, the wing 16 frictionally engages one side of the toe iron, while the toe clip frictionally engages the other side. The sole clips are slightly convex on the sole engaging face, in order to facilitate entry of the sole under the same.

Referring now to the modified form of toe irons disclosed in Figs. 5 and 6 of the drawings, the numeral 17 indicates the toe irons disposed in forwardly converging relationship. Flat, transverse tongues 18 support the toe irons and extend across the ski in side by side relationship and are secured in such position and slideable relative to each other by a grooved anchor plate 19 rigidly mounted to the ski by suitable screws. Adjacent edges of the tongues are formed with matching semi-circular notches 20. A screw 21 extends through the anchor plate, through the circular opening formed by a matching pair of notches and is then threaded in a metallic thimble 22 fixedly embedded in the ski 1.

To adjust this form of toe irons, the screw 21 is removed, the tongues moved in opposite directions until the toe irons are in proper position and a pair of notches 20 are in matching relationship and then the screw is replaced and tightened. The screw being threaded into the embedded thimble prevents splitting of the ski and stripping of the screw hole which would ultimately occur if a wood screw were used and engaged in the wood of the ski.

The heel strap and a buckle unit comprises a flexible metallic heel strap 23, having spaced heel clips 24 projecting inwardly at right angles to the strap. The strap 23 is also provided with a tightening clamp 25 of usual construction.

Each end of the metallic heel strap 23 is enlarged as at 26, and each enlarged portion is provided with two spaced, rectangular openings 27. Sliding rings 28 are mounted on the enlarged portions 26, adjacent the openings 27, to form the complete buckles.

Separate connecting straps 29 are passed through slots 30 in each toe iron and the two free ends of the doubled straps are connected to the buckles as follows: The inner end of each connecting strap is passed from the inside of the enlarged portion 26 through the rear-most opening 27, is extended around the adjacent ring 28, then passed back through the same opening 27 and the end allowed to remain free. The outer ends of the straps are similarly passed through the foremost opening 27. To tighten the strap 29 and draw the heel strap tightly about the heel of the ski boot, the rings 28 are drawn rearwardly, the connecting straps drawn taut and the rings then moved forward until the straps are frictionally engaged against the forward side of the opening 27. Then, any pull on

straps 29 will tend to further tighten the straps in the buckle units, as when the tightening clamps 25 are closed. When the straps 29 and heel strap 23 are tightened, the heel clips 24 engage over the upper portion of the heel and prevent the heel strap from slipping off the heel.

For use on rental skis, the ski bindings heretofore described may be easily and quickly adjusted to conform to the boots of a person who is to use the skis. The toe clamps (either the preferred or modified form) are first adjusted laterally of the skis to snugly engage the sole of the boots, such adjustment being accomplished in the manner heretofore described. Then the sole clips are adjusted so as to engage against the upper edge of the sole and hold the sole from relative vertical movement away from the ski. In the event that sole clips are not used, a toe strap may be used instead, as indicated at T in Figure 1.

After the toe irons and clips are adjusted, the heel strap is placed about the heel of the boot, with the heel clips extending over the upper edge of the heel, the connecting straps are tightened as heretofore described and lastly, the tightening clamp is closed.

The toe irons are preferably of malleable metal, so that their angle of convergence may be changed to conform to various shapes of boot toes.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a ski binding including toe irons, means mounting the toe irons on the ski for relative lateral movement, and means to move the toe irons in opposite directions relative to each other; said last named means comprising a laterally immovable but rotatable transverse bolt mounted adjacent the forward ends of the toe irons, the ends of the bolt being threaded with right and left-hand threads, respectively; grooved nuts threaded on the ends of the bolt, the forward end of each toe iron being notched and engaging over the grooved portion of the corresponding nut.

2. In a ski binding including toe irons, means mounting the toe irons on the ski for relative lateral movement, and means to move the toe irons in opposite directions relative to each other; said last named means comprising a laterally immovable but rotatable transverse bolt mounted adjacent the forward ends of the toe irons, the ends of the bolt being threaded with right and left-hand threads, respectively; and means on the forward end of each toe iron engaging the adjacent portion of the bolt in threaded connection.

JEROME E. BARIEAU.
